UNITED STATES PATENT OFFICE.

LOUIS MEYERS, OF BROOKLYN, NEW YORK.

GARMENT-HANGER SUPPORT.

1,300,444.

Specification of Letters Patent. Patented Apr. 15, 1919.

Application filed December 16, 1918. Serial No. 266,915.

To all whom it may concern:

Be it known that I, LOUIS MEYERS, a citizen of the United States of America, residing at Brooklyn, New York, have invented 5 new and useful Improvements in Garment-Hanger Supports, of which the following is a specification.

This invention relates to garment hanger supports.

10 The object of the invention is to provide a two point garment hanger support particularly adapted for use with what is commonly termed a "wardrobe trunk," which is characterized by two vertically disposed 15 hinged sections, one of which sections is provided with a hinged top.

More specifically, an object of the invention is to provide a pair of parallel garment hanger supports, having hinged sections, so 20 that they may be extended beyond the front line of the section of the trunk to which they are attached to permit the ready removal of a garment hanger supported thereby.

A more specific object is to provide a locking means for the pivoted extensions, which may be operated by pressure at the front end of the extension.

The invention consists of the construction, combination, and arrangement of parts, as 30 herein illustrated, described and claimed.

In the accompanying drawings, forming part hereof, is illustrated a form of embodiment of the invention, in which drawings similar reference characters designate corresponding parts, and in which:

Figure 1 is a perspective view;

Fig. 2 is a vertical section, taken approximately on line 2—2 of Fig. 4, looking in the direction indicated by the arrows;

40 Fig. 3 is a vertical section, taken approximately on line 2—2 of Fig. 4, looking in the direction indicated by the arrows, the top of the trunk and the pivoted extensions of the rods being shown in closed 45 or folded position;

Fig. 4 is a fragmentary detail in plan showing a rod and its supports; and,

Fig. 5 is a fragmentary detail in side elevation of a portion of one of the pivoted 50 extensions of the rods and its immediately connected parts.

Referring to the drawings, 1 and 2 designate respectively the two hingedly connected body parts of a trunk, the section 1 therefore 55 of being provided with a hinged top 3,

all of common and well-known construction.

Secured to the section 1 adjacent its upper end is a U-shaped metal strip 4, provided at its rear end with lugs 5 and at its 60 sides with lugs 6.

Carried by the lugs 5 and 6, adjacent the opposite sides of the section 1, are rods 7 which may be secured to the lugs in any ordinary mechanical way. The rods 7 are 65 provided with pivoted extensions 8, bearing at their outer ends slidable caps 9. The slidable caps 9 are maintained in an extended position by means of coiled springs 10 and are connected to the forward ends 70 of bars 11. The bars 11 are maintained in slidable relation to the extensions 8, as by means of rivets 12 working through slots 13 in the bars and having their inner ends secured to brackets 14, carried on the extensions 8.

The inner ends of the bars 11 are provided with beveled faces 15 arranged to abut the beveled faces 16 of down-turned offset ends 17 of locking bars 18. The locking bars 18 80 are pivoted as at 19 to the side lugs 6 on the frame 4, and the forward ends of the bars 18 are arranged to interlock with shoulders 20 formed on the upper surfaces of the brackets 14.

With the parts in the position shown in Fig. 3, the extensions 8 may be rocked upon their pivots to a horizontal position so that the overturned ends 17 of the bars 18 engage behind the shoulders 20, and maintain the extensions 18 in extended position. Pressure against the caps 9 will overcome the tension of the springs 10 and force the bars 11 backward so that their beveled faces 15 strike the beveled faces 16 90 of the bars 8 effecting the release of the ends 17 of the bars from the shoulders 20 and will permit the extensions 18 to drop to the vertical position shown in Fig. 3, so that the hinged sections 1 and 2 of the trunk 100 may be brought together.

Having thus fully described the invention, what is claimed as new and desired to be secured by Letters Patent is:

1. A garment hanger support comprising 105 the combination of a pair of supported parallel rods each provided with a pivoted extension, locking means for the extensions, and means projecting beyond the ends of the extensions for unlocking the locking means. 110

2. A garment hanger support comprising the combination of a pair of rods each having a pivoted extension, means for locking the extensions in a horizontal position and means slidably carried by the extensions for unlocking the locking means.
3. A garment hanger support comprising the combination of a pair of parallel supported rods each provided with a pivoted extension, and each extension being provided with a depending portion having a shoulder thereon, locking bars pivotally supported and arranged to engage the shoulders, and means for disengaging the locking bars from the shoulders.
4. A garment hanger support comprising the combination of a pair of parallel rods each having a pivoted extension, locking bars arranged to engage the extensions to maintain them in horizontal position, and an unlocking bar maintained in slidable relation to each extension and arranged to contact with the locking bars.
5. A garment hanger support comprising the combination of a pair of parallel rods each having a pivoted extension, locking bars arranged to engage the extensions to maintain them in horizontal position, an unlocking bar maintained in slidable relation to each extension and arranged to contact with the locking bars, and means for nor-

mally maintaining the unlocking bars out of contact with the locking bars.

6. A garment hanger support comprising the combination of a pair of parallel rods each provided with an extension pivotally connected therewith, a locking bar arranged to engage a portion of each extension, a cap disposed at the outer end of each extension, a spring disposed within each cap, and an unlocking bar for each extension having its forward end connected to the corresponding cap and its rear end arranged to contact with the corresponding locking bar when the tension of the spring is overcome.

7. A garment hanger support comprising the combination of a pair of parallel rods each having a pivoted extension and each extension being provided with a depending bracket provided with a shoulder, a locking bar for each rod provided with an offset downturned end having a beveled face and arranged to contact with the shoulder, and an unlocking bar slidably maintained on each extension and each provided with a beveled face arranged to contact when forced in one direction with the corresponding beveled face on the locking bars.

In testimony whereof I have signed my name to this specification.

LOUIS MEYERS.
